RAILWAY SIGNALING SYSTEM.

1,396,888.

Specification of Letters Patent. Patented Nov. 15, 1921.

Application filed December 29, 1915, Serial No. 69,175. Renewed June 9, 1920. Serial No. 387,801.

To all whom it may concern:

Be it known that I, CHARLES F. SCOTT, a citizen of the United States, and a resident of New Haven, in the county of New Haven and State of Connecticut, have invented a new and useful Improvement in Railway Signaling Systems, of which the following is a specification.

My invention relates to alternating-current railway systems, and particularly to multi-track railway systems which are equipped with electrical signaling devices and, at the same time, embody means for utilizing the tracks in common as return conductors and means for minimizing the inductive disturbances that may be imposed on adjacent electrical circuits by reason of the power currents flowing in the railway systems.

In alternating-current railway systems, it is usual to insert insulating joints at suitable points in the rails in order to provide insulated block-sections for the signaling systems. Each of these block-sections constitutes a section of the track that is protected by an indicating device which may be a semaphore or any other convenient signaling means. The operation of this signaling device is usually effected by means of a relay excited by signaling currents that are confined to the separate block-sections and are derived from a source of power independent of that furnishing the propulsion currents.

In order that the propulsion currents may flow over the tracks of a multi-track railway system, impedance bonds are usually inserted on each side of the insulating joints defining the block sections of each track and are connected between the track-sections and tracks in such manner that the propulsion currents will normally divide themselves between the rails of the several tracks.

Adjacent impedance bonds are interconnected by means of taps disposed at the mid-points of their windings so that the propulsion current from one rail traverses one-half of each winding in one direction, and the current from the other rail traverses the other half of the winding in the opposite direction. Since the currents in the two halves of the windings neutralize each other in their magnetizing action on the core members of the impedance bonds, the propulsion currents are afforded a path of low impedance for their flow along the track. The

several tracks are connected to one another through connectors extending between corresponding impedance bonds, usually those at the ends of the block sections of the signaling system. The impedance bonds, however, preclude the flow of the signaling current through their windings because of the high impedance they offer to alternating currents tending to flow therethrough in a single direction only. As a consequence, the signaling currents are forced to flow through the signaling relay which, in turn, controls the operation of the signaling device to indicate the conditions obtaining upon a particular block-section of the railway system.

In alternating-current railway systems, it is desirable to provide means for minimizing the inductive disturbances that may arise from the flow of the propulsion currents therein. A very effective means for accomplishing this object contemplates the insertion of a number of series transformers at spaced intervals in a railway system, the primary windings of the transformers being connected in series-circuit relationship with the trolley or third-rail conductor, and the secondary windings thereof being connected through impedance bonds to the track rails and in shunt to the aforementioned insulating joints positioned in the rails. By confining the return flow of the trolley current to the track, the inductive effects arising from the current flow over the trolley conductor are substantially neutralized. This system for minimizing inductive interferences is fully described in my co-pending patent application, Serial No. 170, filed January 2, 1915, and which matured into Patent No. 1,196,300, Aug. 29, 1916. By inductively interlinking the track and the trolley conductor, as mentioned above, electro-motive forces are impressed at intervals in the track which compensate for the impedance of the track and serve to confine the flow of the propulsion currents to the track in preference to the earth. If it is desired to interconnect the tracks of a multi-track railroad system at points near the middle of the block-sections, it will be necessary to confine the alternating currents adapted to operate the signaling apparatus to the separate block-sections in order to afford the proper protection to the traffic accommodated by the railroad. Therefore, in conjunction with the above-mentioned means for minimizing

the inductive interferences, I also provide means for permitting the signaling currents to flow substantially unimpeded in each of the block-sections of the several tracks, at 5 the same time, insuring that the signaling currents of the separate block sections be maintained independent of one another.

An object of my invention is to provide means, in a multi-track railway system in 10 which the block-sections of the separate tracks are not correspondingly positioned, for dividing each track circuit into a plurality of block sections for signaling purposes without breaking the electrical conductivity of any one track circuit for the 15 return flow of the propulsion currents and, at the same time, permit the signaling currents to flow substantially unimpeded in the separate block sections. Moreover, the several tracks are to be connected in parallel relationship in order that they may, in combination, constitute a return conductor of low impedance for the return flow of the 20 propulsion currents. In conjunction with the aforementioned means, I inductively interlink the trolley and the tracks with one another in order to confine the return flow 25 of the trolley currents to the tracks so as to minimize the inductive disturbances that 30 may be impressed upon any adjacent electrical circuit, such as an intelligence-transmission circuit.

For a better understanding of the nature 35 and scope of my invention, reference may be had to the following description and the accompanying drawing in which the single figure is a diagrammatic representation of a railway system embodying a form of my invention.

40 Referring to the drawing, a source of alternating current (not shown) supplies propulsion currents to trolley conductors 1 and 2 and to their associated tracks 3 and 4, respectively, the latter, in combination, constituting a path for the return flow of the 45 propulsion currents. Spaced insulating joints 5 are inserted at intervals in the trolley conductor 1, and correspondingly positioned insulating joints 6 are inserted in 50 the trolley conductor 2. It is presumed that the block sections comprising the insulated track-sections are not correspondingly placed in the tracks 3 and 4, and, for convenience, I assume, in this instance, that the ends of the 55 block sections of the track 3 are substantially positioned at the mid-points of the block sections of the track 4. Insulating joints 7 are inserted in each of the rails of the track 3 at spaced intervals to define the 60 block sections thereof, and other insulating joints 7^a of the track 4 are arranged in staggered relationship to the insulating joints 7 of the track 3 to define the block sections 65 of the track 4. Insulating joints 8 are inserted in each of the rails of the track 3 at

points corresponding to the location of the insulating joints 7^a of the track 4 and, similarly, insulating joints 8^a of the track 4 are inserted at points corresponding to the location of the insulating joints 7 of the track 3. 70 It is apparent, therefore, that the block sections of the tracks 3 and 4 are disposed in staggered relationship with respect to one another. I propose, however, to interconnect the tracks to each other both at the ends 75 and the mid points of the block sections and, at the same time, to inductively interlink the trolley conductors and the tracks to each other in order that the return flow of the propulsion currents may be confined conjointly 80 to the tracks.

Each of the track sections intermediate the insulating joints 7 and 7^a of the tracks 3 and 4 respectively, constitutes a block-section of the signaling system, each block section being provided with a signaling device 9 and a track transformer 10, a primary winding 11 of which is connected to mains 12 of the signaling supply circuit, and a secondary winding 13 of which is connected across the 85 rails of a track section. As this is a usual arrangement for the signaling system, further explanation thereof is not deemed necessary.

90 Adjacent to each other and on both sides of the insulating joints 7 and 7^a, impedance bonds 14 and 14^a, respectively are inserted, which comprise current-carrying windings provided with taps 15 and 15^a, respectively, at their mid-points.

95 An intelligence-transmission conductor 16, shown as a telegraph circuit, is disposed in proximity to the trolley conductors 1 and 2 and the tracks 3 and 4 and is, therefore, under the inductive influences arising from 100 the power currents flowing in the railway system. It is important, therefore, to minimize the inductive disturbances that may be impressed upon the conductor 16 in order to insure satisfactory operation of the 105 telegraph circuit. At the same time, the tracks are interconnected with each other in order to provide a return conductor of low impedance for the propulsion currents. In addition, it is to be understood that the signaling devices 9 must operate independently of 110 one another in order to amply protect the railway traffic accommodated upon the railway system. To this end, transformers 17 and 18 are provided, each of which 115 comprises a plurality of windings that are connected to the railway circuits, as will be hereinafter described.

120 Since the railway circuit comprising the trolley conductor 1 and the track 3 is similar in all respects to the other railway circuit, my description will be confined to the operation of the former.

125 Referring particularly to a block section 130 formed in the track 3, it will be noted that

the insulating joints 8 are inserted substantially midway in the block section. Since the signaling currents for operating the signaling device 9 must be shunted across the insulating joints 8, mutually inductively related windings 20 and 21 are connected across them in order to make the rail sections electrically continuous. Taps 22 and 22^a are provided at the mid-point of the windings 20 and 21, respectively, and are connected through leads 23 and 24 to the terminals of an impedance coil 25. The windings 20 and 21 are so wound upon a common core member (not shown) that the simultaneous and oppositely directed flow therethrough of the signaling currents will be substantially unimpeded. A winding 26, wound on the same core member as the windings 20 and 21, is connected across the insulating joint 5 inserted in the trolley conductor 1, and a second winding 26^a is connected to the trolley conductor 2 in shunt to the insulating joint 6 which corresponds to the insulating joint 5 of the trolley conductor 1. A secondary winding 27 is connected, in a usual manner, through impedance bonds 14 to the track 4. The windings 26^a and 27 constitute primary and secondary windings, respectively, of a series transformer that inductively interlinks the trolley conductor 2 with the track 4. This series transformer may be considered as being embodied in the transformer 18 which, for convenience, comprises a single core member (not shown) having the windings 20—21, 26—26^a and 27 wound thereupon in proper relationship, as hereinbefore explained.

Reference may now be had to the transformer 17 which resembles the transformer 18 in all respects, with the exception that those transformer windings of the transformer 18 which are associated with the track 3 are, in the transformers 17, associated with the track 4, and vice versa. For instance, windings 20^a and 21^a are connected across the insulating joints 8^a of the track 4, the winding 20^a being provided with a tap 22^b disposed at its mid-point and connected through a conductor 23^a to one terminal of an impedance coil 25^a. The winding 21^a is similarly provided with a tap 22^c which is connected by a conductor 24^a to the other terminal of the impedance coil 25^a. A primary winding 26^b is connected in shunt to the insulating joint 5 of the trolley conductor 1, and a secondary winding 27^a is connected to the mid-points of impedance bonds 14^b which are disposed on both sides of the insulating joints 7 in the track 3. Another winding 26^c corresponding to the winding 26 of the transformer 18, is connected in shunt to the insulating joints 6 of the trolley conductor 2. From the foregoing description, it will be noted that the trolley conductors 1 and 2 are inductively

interlinked at alternate points with the track 3 and with the track 4.

It will be understood that, when the return propulsion currents are allowed to flow through the ground, a very large inductive loop is thereby formed and that the inductive interference with any nearby intelligence-transmission conductor therefore tends to become excessive. By dividing the propulsion currents, in the manner herein-after to be described, among the various tracks of the railway system, I am able to materially reduce the size of the inductive loop formed and subsequently decrease the amount of inductive interference.

As mentioned above, the two tracks 3 and 4 are electrically interconnected to provide a return conductor of low impedance for the propulsion currents, and this is effected through the impedance coils 25 and 25^a. To illustrate: The winding of the impedance coil 25 is provided with a tap 28 at its mid-point which, in turn, is connected by a conductor 29 to a mid-point tap 30 on the winding 27, the latter being connected through the impedance bonds 14 and 14^a to the track 4. Similarly, the winding of the impedance bond 25^a is provided with a tap 28^a at its mid-point which is connected, by a conductor 29^a, to a mid-point tap 30^a of the winding 27^a, the latter being connected through impedance bonds 14^b to the track 3. Assume that alternating propulsion current is traversing the track 3. By reason of the discontinuity of the rails of track 3, because of the insertion of the insulating joints 8, a portion of this current will traverse the entire length of windings 20 and 21 and the other portion will traverse simultaneously portions only of the windings 20 and 21 in its endeavor to bridge the insulating joints 8. The mid-points of the windings 20 and 21, as explained above, are connected to the terminals of the impedance coil 25, the mid-point 28 of which is connected, through the conductor 29, to the mid-point 30 of the winding 27.

By reason of the relatively high impedance offered by the windings 20 and 21 to the flow therethrough of alternating currents traversing the two rails of the track 3 in the same direction, a portion of these currents will take the path afforded by the conductors 23 and 24, extending respectively from the mid-points of the windings 20 and 21, the winding 25, which offers substantially zero impedance, and the conductor 29 to the mid-point 30 of the winding 27.

The terminals of the winding 27 are connected to mid-points 15 and 15^a of the impedance bonds 14 and 14^a that are connected across the rails of the track 4. By introducing propulsion currents from the track 3, as explained above, through the conductor 29, the mid-point 30 of the winding 27

130

and either the mid-points 15 or 15^a of the impedance bonds 14 and 14^a, respectively, the currents are permitted to flow to the track 4, which is desired, since the two tracks 3 and 4 are thus electrically connected to each other to furnish conjointly a return path of low impedance for the propulsion currents. The impedance coils 25 and 25^a, therefore, furnish means for interconnecting the mutually inductively related windings 20 and 21 of the track 3 and the mutually inductively related windings 20^a and 21^a of the track 4 to the secondary windings 27 and 27^a, respectively, of the tracks 3 and 4.

15 As a consequence, the tracks 3 and 4 are electrically connected to each other, as regards the propulsion currents, but the separate block-sections of the tracks are maintained electrically independent of one another, as regards the signaling currents.

Assuming that the block section 19 is open to traffic, the signaling device 9 indicates an open block since the signaling currents traverse freely the mutually inductively related windings 20 and 21 of the transformer 18 by being offered negligible impedance only. The signaling currents flowing simultaneously and in opposite directions through the said windings neutralize the inductive effects 30 that would necessarily be occasioned by a uni-directional current flow therethrough. The impedance coil 25, while connected across the windings 20 and 21, precludes the flow therethrough of the signaling currents, 35 inasmuch as it acts in the same manner as the impedance bonds 14. The signaling currents, therefore, are forced to flow through the associated relay of the signaling device 9.

When a railway train, such as indicated at 40 31, bridges the block section 19, the signaling currents are shunted through the trucks of the train, thereby short-circuiting the signaling device 9 which operates to indicate that a train occupies the block 19. It will 45 be noted that the impedance bonds 14^b confine the signaling currents to the insulated block section 19, thereby permitting each block section to be operated independently of the others. The propulsion currents supplied to the train 31 will traverse the primary winding 26^b of the transformer 17, and the primary winding 26 of the transformer 18, which windings are connected across the insulating joints 5 inserted in the trolley conductor 1. The flow of the trolley currents 50 through the primary windings of the transformers 17 and 18 will induce compensating electromotive forces in the secondary windings whereby the return flow of the propulsion currents may be confined to the tracks 3 and 4. The secondary winding 27^a is directly connected to the track 3 through the impedance bonds 14^b and, consequently, the return flow of a portion of the propulsion 55 currents may be directed therethrough in the

usual manner. The propulsion currents flowing from the train 31 will return through each of the rails of the block section 19 and through at least a portion of the windings 20 and 21 which, as before mentioned, are connected across the insulating joints 8. Under the particular conditions assumed, substantially one-half of the propulsion currents may flow through the whole of the windings 20 and 21 and return through the track 3. The other half of the propulsion currents may flow simultaneously from the taps 22 and 22^a along the conductors 23 and 24 and oppositely through the winding of the impedance coil 25 to the mid-point tap 28. From the tap 28 they may flow through the conductor 29 to the tap 30 of the secondary winding 27 and then traverse one-half of the secondary winding 27 to the impedance bond 14 by means of which they are directed into the rails of the track 4. The portion of the propulsion current flowing through the impedance coils 25 and 25^a will be offered negligible impedance since the induction resulting from the oppositely-directed current flow therethrough is substantially neutralized. It will be noted that the transformers 17 and 18 provide means for interchanging the current flow in the tracks 3 and 4, inasmuch as the 95 transformers 17 and 18 are similar, in all respects, the corresponding windings thereof, however, being connected to the different railway circuits, as hereinbefore explained.

It may be desirable, under certain operating conditions, to design the several circuits so as to have a uniform impedance per unit length of track. In this manner, the return flow of the propulsion currents will be substantially equally divided between the 100 tracks 3 and 4 which results in providing a return conductor of very low impedance. This is apparent by considering that the trolley or primary current supplied to the train 31 will flow through the primary winding 26 of the transformer 18, necessitating that a portion of the return current flow through the coils 20 and 21. One-half of the return current will, in this instance, return through the track 3, and the other half of the propulsion current will flow through portions only of the coils 20 and 21 to the mid-point taps 22 and 22^a by means of which it is conducted to the track 4.

From the foregoing description, it will be 110 observed that the return flow of the propulsion current is confined to the tracks, thereby minimizing the inductive disturbances that may be impressed upon the telegraph circuit 16. At the same time, each 115 block section is electrically continuous to the signaling currents and provides a path of low impedance therefor. Moreover, the tracks 3 and 4 are electrically interconnected in order that the propulsion currents may 120 125 130

be divided between them, so as to provide a low impedance path for their return flow.

While I have shown one embodiment of my invention, it will be understood by those skilled in the art that many modifications may be made therein without departing from the spirit and scope of the appended claims.

I claim as my invention:

1. In an electric railway system, the combination with two tracks each having an associated trolley conductor, said tracks comprising insulated block-sections which are arranged in staggered relationship in the tracks, and insulating joints inserted at corresponding points in both tracks, of means for inductively interlinking each trolley conductor to its associated track, mutually inductively related windings for bridging the insulating joints positioned at intermediate points in the block-sections, and equalizing means for equalizing the return flow of the propulsion currents in the two tracks, said equalizing means comprising inductively related coils connected between said tracks and, in turn, inductively interlinked with said means which serve to interlink said trolley conductor and said track. 70
2. In an electric railway system, the combination with two tracks each having an associated trolley conductor and comprising a plurality of insulated block sections, and insulating joints which are arranged in staggered relationship with respect to one another in the tracks inserted in the rails intermediate the ends of the block sections, of current-carrying windings connected in shunt to said insulating joints and being mutually inductively related to one another, and impedance coils having their terminals connected to the mid-points of said current-carrying windings of one track and their mid-points connected to the other track. 80
3. In an electric railway system, the combination with two tracks each having an associated trolley conductor, said tracks comprising insulated block-sections which are arranged in staggered relationship in the tracks, and insulating joints inserted at corresponding points in both tracks, of transformers located at the insulating joints in the tracks, said transformers comprising windings for inductively interlinking both trolley conductors alternately to said tracks, and mutually inductively related windings for bridging the insulating joints positioned in the rails intermediate the ends of the block sections, and impedance coils having their terminals connected to the mid-points of alternate groups of said mutually inductively related windings and their mid-points connected alternately to the mid-points of the aforementioned windings associated with the tracks whereby the return flow of the propulsion currents in the tracks may be equalized. 90
4. In an electric railway system, the combination with two tracks each having an associated trolley conductor, said tracks comprising block-sections which are arranged in staggered relationship with respect to one another in the tracks, and insulating joints inserted at corresponding points in both tracks and both trolley conductors, of transformers for inductively interlinking the trolleys and tracks to one another comprising means for bridging the insulating joints at intermediate points in the block-sections, and equalizing means for equalizing the return flow of the propulsion currents in the two tracks, said equalizing means comprising inductively related coils connected between said tracks and, in turn, inductively interlinked with said means which serve to interlink said trolley conductor and said track. 100
5. In an electric railway system, the combination with two tracks each having an associated trolley conductor, said tracks comprising block-sections which are arranged in staggered relationship in both tracks, insulating joints inserted at corresponding points in both tracks and both trolley conductors, of transformers located at the insulating joints for inductively interlinking both trolley conductors with the tracks, said transformers comprising mutually inductively related windings for bridging the insulating joints intermediate the ends of the block-sections, and equalizing means for electrically interconnecting said tracks to each other whereby the return flow of the propulsion currents may be divided between both tracks, said equalizing means comprising inductively related coils connected between said tracks and, in turn, inductively interlinked with said means which serve to interlink said trolley conductor and said track. 110
6. In an electric railway system, the combination with two tracks each having an associated trolley conductor, spaced insulating joints inserted at corresponding points in the tracks and the trolley conductors, and impedance bonds connected to each track on both sides of alternate insulating joints and staggered in position with respect to one another in the two tracks, of transformers for inductively interlinking the tracks and trolley conductors with one another, each of said transformers comprising a common core member, primary windings connected in shunt to the insulating joints inserted in the trolley conductors, a secondary winding which is connected through said impedance bonds to one track and mutually inductively related windings which are connected across insulating joints in the other track, and impedance coils having their terminals connected to mid-points of said mutually inductively related windings and their mid-points connected to mid-points of said secondary windings. 120

7. In an alternating-current railway signaling system of the type wherein the two rails of each track serve as parallel paths for the return flow of propulsion currents and also as the two sides of the signaling current circuits, the combination of a pair of tracks, each comprising a pair of rails, an insulating joint in each of said rails, a transformer having three windings, each of 10 said windings having a mid-tap, two of said windings being connected respectively across the insulating joints of the rails of one of said tracks, an induction device connected between the mid-taps of said two windings, 15 said inductance device having a mid-tap connected to the mid-tap of the third winding of said transformer, and a pair of additional inductance devices, one of said additional inductance devices connecting the rails of the 20 other of said tracks on each side of said insulating joints, said additional inductance devices having mid-taps connected respectively to the ends of said third transformer winding.

25 8. A system as specified in claim 7, including two additional windings on the transformer, a trolley conductor for each track, and an insulating joint in each of said trolley conductors, said additional 30 transformer windings being connected across the insulating joints of the respective trolley conductors.

9. In an alternating-current railway signaling system of the type wherein the two rails of each track serve as parallel paths for the return flow of propulsion currents and also as the two sides of the signaling current circuits, the combination of a pair of tracks, each comprising a pair of rails, 35 an insulating joint in each of said rails, an inductance device connecting the rails of one of said tracks on each side of said insulating joints, whereby the signaling currents on opposite sides of said insulating 40 joints are rendered independent of each other, each of said inductance devices having a mid-tap, an additional inductance device connecting said mid-taps, said additional inductance device also having a mid-tap, 45 bridging means for bridging the insulating joints of the other track, and means associated with the last-mentioned mid-tap and said bridging means for equalizing the 50 propulsion currents flowing across said insulating joints in the same direction in all of said rails.

55 10. A system as specified in claim 9, including a trolley-conductor for each track, an insulating joint in each of said trolley conductors, and means bridging said trolley conductor joints for confining the flow of 60 return-current to said rails.

65 11. In an alternating-current railway signaling system of the type wherein the two rails of each track serve as parallel paths

for the return flow of propulsion currents and also as to the two sides of the signaling current circuits, the combination of a pair of tracks, each comprising a pair of rails, an insulating joint in each of said rails, 70 and means comprising windings bridging the insulating joints in the respective tracks for forming a continuous path for propulsion currents and inductively related windings associated with the two tracks whereby the return flow of propulsion currents across said insulating joints is equalized in all four rails, and whereby the signaling currents in the two tracks are kept independent of one another. 75

80 12. A system as specified in claim 11, including a trolley conductor for each track, an insulating joint in each of said trolley conductors, and means bridging said trolley-conductor joints for confining the flow 85 of return-current to said rails.

89 13. In an alternating-current railway signaling system of the type wherein the two rails of each track serve as parallel paths for the return flow of propulsion currents and also as the two sides of the signaling current circuits, the combination of a pair of tracks, each comprising a pair of rails, an insulating joint in each of said rails, a pair 90 of inductively related windings bridging the insulating joints of the respective rails of one of said tracks, each of said windings having a mid-tap, bridging means bridging the insulating joints of the other track, and means associated with said mid-taps and 95 with said bridging means for equalizing the propulsion currents flowing across said insulating joints in the same direction in all of said rails. 100

105 14. A system as specified in claim 13, including a trolley conductor for each track, an insulating joint in each of said trolley conductors, and means bridging said trolley-conductor joints for confining the flow of return-current to said rails. 110

115 15. In an electrical transmission system, the combination of two pairs of conductors adapted for the simultaneous transmission of two separate component alternating currents, the two conductors of each pair serially constituting the circuit of one of said component currents and in parallel one side of the circuit of the other of said component currents, an insulating joint inserted in each of said conductors, a transformer having 120 three windings, each of said windings having a mid-tap, two of said windings being connected respectively across the insulating joints of the conductors of one of said pairs, an inductance device connected between the 125 mid-taps of said two windings, said inductive device having a mid-tap connected to the mid-tap of the third winding of said transformer, and a pair of additional inductance devices, one of said additional in- 130

- ductance devices connecting the conductors of the other of said pairs on each side of said insulating joints, said additional inductance devices having mid-taps connected respectively to the ends of said third transformer winding.
16. A system as specified in claim 15, including two additional windings on the transformer, a third conductor for each pair of conductors, and an insulating joint in each of said third conductors, said additional transformer windings being connected across the insulating joints of the respective third conductors.
- 15 17. In an electrical transmission system, the combination of two pairs of conductors adapted for the simultaneous transmission of two separate component alternating currents, the two conductors of each pair serially constituting the circuit of one of said component currents and in parallel one side of the circuit of the other of said component currents, an insulating joint inserted in each of said conductors, an inductance device connecting the conductors of one of said pairs on each side of the insulating joints, whereby the first mentioned component currents on opposite sides of said insulating joints are rendered independent of each other, each of said inductance devices having a mid-tap, an additional inductance device connecting said mid-taps, said additional inductance device also having a mid-tap, bridging means for bridging the insulating joints of the other pair of conductors, and means associated with the last mentioned mid-tap and said bridging means for equalizing the second mentioned component currents flowing across said insulating joints in the same direction in all of said conductors.
18. A system as specified in claim 17, including a third conductor for each pair, an insulating joint in each of said third conductors, and means bridging said third conductor joints, whereby the sum of the currents in said third conductors and the sum of the currents in said pairs of conductors may be substantially equalized.
- 45 19. In an electrical transmission system, the combination of two pairs of conductors adapted for the simultaneous transmission of two separate component alternating currents, the two conductors of each pair serially constituting the circuit of one of said
- component currents and in parallel one side of the circuit of the other of said component currents, an insulating joint inserted in each of said conductors, and means comprising windings bridging the insulating joints in the respective pairs for forming a continuous path for the second mentioned component currents and inductively related windings associated with the two pairs of conductors whereby the flow of said second component currents across said insulating joints is equalized in all four conductors, and whereby the first mentioned component currents in the two pairs of conductors are kept independent of one another.
20. A system as specified in claim 19, including a third conductor for each pair of conductors, an insulating joint in each of said third conductors, and means bridging said third conductor joints, whereby the sum of the currents in said third conductors and the sum of the currents in said pairs of conductors may be substantially equalized.
- 25 21. In an electrical transmission system, the combination of two pairs of conductors adapted for the simultaneous transmission of two separate component alternating currents, the two conductors of each pair serially constituting the circuit of one of said component currents and in parallel one side of the circuit of the other of said component currents, an insulating joint inserted in each of said conductors, a pair of inductively related windings bridging the insulating joints of the respective conductors of one of said pairs, each of said windings having a mid-tap, bridging means bridging the insulating joints of the other pair, and means associated with said mid-taps and with said bridging means for equalizing the second mentioned component currents flowing across said insulating joints in the same direction in all of said conductors.
- 30 22. A system as specified in claim 21, including a third conductor for each pair of conductors, an insulating joint in each of said third conductors, and means bridging said third conductor joints, whereby the sum of the currents in said third conductors and the sum of the currents in said pairs of conductors may be substantially equalized.
- 35 40 45 50 55 60 65 70 75 80 85 90 95 100 105
- In testimony whereof, I have hereunto subscribed my name this 22nd day of Dec. 1915.

CHARLES F. SCOTT.
